UNITED STATES PATENT OFFICE.

JOSEF GEIGER, OF AUGSBURG, GERMANY, ASSIGNOR TO MASCHINENFABRIK AUGSBURG-NUERNBERG, AKTIENGESELLSCHAFT, OF AUGSBURG, GERMANY, A CORPORATION OF GERMANY.

DIESEL LOCOMOTIVE.

Application filed December 24, 1927, Serial No. 242,494, and in Germany January 3, 1927.

This invention relates to Diesel-locomotives and more particularly to the type of Diesel-locomotives comprising a Diesel-motor, a compressor driven thereby and a pressure-air conduit supplying pressure-air from said compressor to the working cylinders of the locomotive. In locomotives of this type it is desirable, in order to increase the efficiency of the pressure-air transmission plant 5 to pre-heat the pressure-air before entering the locomotive cylinders by means of a special heating device.

More particularly, this invention consists in a novel arrangement of said heating device. According to this invention the heating device is mounted on the rear side of the Diesel-motor so as to extend in longitudinal direction of the locomotive. By so arranging the heating-device, the valve-gear, the 10 fuel-pumps and the further appliances which are provided on the other side or front of the Diesel-motor will be easily accessible to the attendant. This is of great importance, especially on account of the fact that 15 the heating device, even in case of greatest possible insulation, will always have a temperature of from 160-170° C. at its surface. This high temperature of the heating device is a great inconvenience for the attendant and 20 a constant source of danger in case of coming accidentally in contact with the heating device.

The accompanying drawing shows an example of a Diesel-locomotive of the above-mentioned type comprising the novel arrangement of the heating device according to this invention, Fig. 1 being a longitudinal view and Fig. 2 a front view of a Diesel-locomotive constructed according to this invention.

Referring now more particularly to the drawing, *a* represents a Diesel-motor, *b* a compressor driven by said motor, said compressor supplying the pressure-air generated 45 therein through the heating device *c* to the conduit *d* and from here to the cylinders *e* of the locomotive. Heat is applied to the heater by means of exhaust gases of the Diesel motor which traverse the length of the heater *c* within the pipe *f*. The hot exhaust gases from the motor are collected by the manifold or pipe *f* which enters the heater at *g* and leaves the heater at *h* to exhaust to atmosphere. The pressure air also traverses the

length of the heater *c* and passes around the 55 pipe *f* thus becoming heated through contact with it. Preferably, as shown by the arrows, the air travels opposite to the direction of flow of the exhaust gases through the passages. As above indicated, according 60 to this invention, the heating device for the pressure-air is mounted on the rear of the Diesel-motor in longitudinal direction of the latter and of the locomotive as a whole. By so arranging the heating device the entire 65 space extending in longitudinal direction of the locomotive in front of the Diesel-motor will be available for purposes of attendance at the same time providing free access to the valve-gear, the fuel-pumps and other 70 appliances of the Diesel-motor. In addition to this, the heating device may be constructed in a more compact form, this resulting in the additional advantage of further reducing the heat losses in the heating device. This 75 reduction of the heat losses is due to the fact that some greater part of the surface of the heating device is positioned in close proximity to the cylinders of the Diesel-motor, which on account of the necessity of using hot 80 cooling water are always in hot condition, thus reducing the heat losses arising in the direction towards the cylinders of the Diesel-motor.

A further advantage of the construction according 85 to this invention consists therein, that the pressure-air and exhaust pipes leading to the heating device will be considerably reduced in length, this doing away with a further source of heat losses. In addition to 90 this, there will be a considerable saving due to reduction of the weight of the several parts and the smaller space required by the same. On the one hand, therefore, the efficiency of the heating device and also the efficiency of the pressure-air transmission plant 95 will be essentially increased, and on the other hand the quantity of heat which passes into the attendant's space will be reduced, thereby rendering conditions more agreeable for 100 the attendant.

I claim:

1. In a Diesel-locomotive, the combination of a Diesel-motor, a compressor driven thereby, working cylinders for said locomotive, a supply conduit for supplying pressure-air from said compressor to said cylinders, a heating device for pre-heating said supply

conduit, said heating device being mounted on one side of said motor in longitudinal direction of said locomotive, and an attendant's space on the other side of said motor, said 5 space extending in longitudinal direction of said motor and said locomotive, substantially as described and for the purposes set forth.

2. In a Diesel-locomotive, the combination 10 of a Diesel-motor mounted centrally to said locomotive in longitudinal direction thereof, working cylinders for said locomotive, a compressor driven by said motor, a supply-conduit for supplying pressure-air from said

compressor to said cylinders, a heating device for pre-heating said supply-conduit, said 15 heating device being mounted on said Diesel-motor on one side thereof and in longitudinal direction of said locomotive, and an attendant's space on the other side of said motor, said space extending in longitudinal direction 20 of said motor and said locomotive, substantially as described and for the purposes set forth.

In testimony whereof I have affixed my signature.

JOSEF GEIGER.
